Filed Nov. 1, 1966, Ser. No. 4,506

Term of patent 7 years

(Cl. D42—7)

Fig. 1.

Fig. 4.

Fig. 2.

Fig. 3.

FIG. 1 is a front elevational view of a clock radio showing my new design, the essential features of which are shown in full lines and reside primarily in the particular arrangement of the hour pips in combination with the dial panel therebelow.

FIG. 2 is a reduced side elevation view, the opposite side being substantially a mirror image thereof.

FIG. 3 is a front perspective view thereof.

FIG. 4 is an enlarged, sectional view of the front face only of the control panel taken along the line 4—4 of FIG. 1.

I claim:

The ornamental design for a clock radio, as shown and described.
